(57) **CLAIM**

I claim the ornamental design for the global position tracking device, as shown and described.

DESCRIPTION

FIG. 1 illustrates a perspective view of a global position tracking device mounted to a user's head through strap;
FIG. 2 illustrates a front plan view thereof;
FIG. 3 illustrates a back plan view thereof;
FIG. 4 illustrates a top plan view thereof;
FIG. 5 illustrates a bottom plan view thereof;
FIG. 6 illustrates a right side plan view thereof; and,
FIG. 7 illustrates a left side plan view thereof.
The broken line showing of structural features is included for the purpose of illustrating non-claimed subject matter and forms no part of the claimed design.
